UNITED STATES PATENT OFFICE.

ANSON GARDNER BETTS, OF TROY, NEW YORK.

ELECTROLYTIC PROCESS.

No. 918,650.

Specification of Letters Patent.

Patented April 20, 1909.

Application filed December 23, 1908. Serial No. 468,975.

To all whom it may concern:

Be it known that I, ANSON GARDNER BETTS, a citizen of the United States, residing at Troy, in the county of Rensselaer, and State of New York, have invented certain new and useful Improvements in Electrolytic Processes, of which the following is a specification.

This invention relates to electrolytic processes for solutions, in which processes reducible compounds are formed at the anode or from the anode products, and it is not desired that they should be again reduced at the cathode.

The object of my invention is to overcome cathodic reduction in such processes simply and at slight cost.

In electrolytic processes for making in solution reducible substances, for example alkali and alkaline earth chlorates and hypochlorites from the corresponding chlorids, it is desirable for reasons well-known in the art that no diaphragms should be used, and considerable loss of the chlorates etc. produced by the anode reactions generally results from the reducing action of the cathode. I overcome this difficulty by the use of a cathode of a metal, preferably of magnesium, not reducible from its compounds at the cathode by the electrolysis of the solution.

I have found by experiment that with a cathode of magnesium in the manufacture of chlorates and hypochlorites, there is little or no reduction at the cathode, which I explain by the great oxidizability of the magnesium superficially, so that the surface of the magnesium cathode is always covered with a thin porous layer of the non-conductor, magnesia, probably in hydrated form, which serves as a thin everpresent diaphragm, preventing the contact of more than small portions of the electrolyte and contained reducible compound with the actual cathode surface.

The hydrogen produced, after leaving the cathode has lost its reducing power, it being a well-known fact that hydrogen in its ordinary state is relatively inactive, as a consequence of which after leaving the cathode surface it bubbles away through the solution untouched.

The objection, above referred to, to diaphragms, disappears when the diaphragm is thin and is at the cathode surface itself, and partial success has been claimed for the use of magnesium and calcium salts in the electrolytes, for the purpose of continually pro-

ducing a film of insoluble hydroxid at the cathode, but this plan is not efficient and is much less perfect in its action than is that of a magnesium cathode, for instance, probably 60 for such reasons as the following.

The film forming on the cathode by oxidation in my method is probably thinner and harder and more strongly attached, hardly breaking away at all, while the deposited film 65 in the old method adheres to the cathode very little or not at all, so that it is continually exposing the platinum, iron, carbon or other cathode with its strong reducing power.

By my method it is not necessary to have any salts of magnesium, calcium etc. in the solution, so that none of the current is used for the decomposition of such salts.

My method is especially useful in the production of hypochlorites for bleaching purposes, having the advantage over the well-known process using the addition of chromates for the purpose of securing high current efficiency, of producing a colorless solution.

In trying to make hypochlorites with a cathode of aluminum, which is almost as oxidizable as magnesium, I found that the caustic generated at the cathode dissolved 85 the aluminum rapidly, and the loss of aluminum was found to be very great in contrast to magnesium, of which the hydroxid is not soluble in caustic solutions.

I do not believe that it is necessary that 90 the cathode used in practicing my invention should consist of a single elementary substance in a pure state. Obviously an alloy which oxidizes in the solution with the production of an irreducible coating, not a conductor of electricity, might also serve, and operate without serious reduction of the reducible compounds in the solution, for the same reason as pointed out in the case of magnesium.

The term "irreducible" is used as referring to the conditions under which the oxidizing i. e. reducible, compounds are produced, and is not used in the sense that the substance in question is irreducible by any process whatever.

What I claim as new and desire to secure by Letters Patent, is:

1. The process of electrolytic oxidation which consists in electrolyzing a solution containing an oxidizable compound with a cathode oxidizable in contact with the solution

with the production of a coating unreduced by electrolysis of the solution.

2. The process of oxidizing a compound in solution which consists in electrolyzing the 5 solution with a cathode which oxidizes with the production of a coating not reduced by the electrolysis, and insoluble in the solution at the cathode.

3. The process of producing a reducible 10 compound in solution which consists in electrolyzing the solution containing a compound from which said reducible compound is produced, with a metallic cathode which oxidizes superficially with the production of 15 a coating of a non-conductor of electricity, unreduced by the electrolysis of the solution.

4. The process of producing a reducible 20 compound in solution, which consists in electrolyzing the solution containing a compound from which said reducible compound is produced, with a suitable anode and a cathode which forms with one of the ions of the solution, a compound irreducible by the electrolysis of the solution and not soluble 25 in the solution in the neighborhood of the cathode.

5. The process of producing a reducible 30 compound in solution, which consists in electrolyzing the solution containing a compound from which said reducible compound is produced, with a suitable anode and a cathode of

a metal forming a coating of an insoluble hydroxid, irreducible by the electrolysis of the solution.

6. The process of producing a reducible 35 compound in solution which consists in electrolyzing the solution containing a compound from which said reducible compound is produced, with a cathode of an alkaline earth metal. 40

7. The process of producing oxidizing compounds which consists in electrolyzing a solution of a halogen compound with a suitable anode and a cathode of magnesium. 45

8. The process of producing oxidizing 45 compounds which consists in electrolyzing a solution containing alkali halid with a suitable anode and a cathode of magnesium.

9. The process of producing a reducible 50 compound in solution which consists in electrolyzing a solution containing a compound from which said reducible compound is produced, with a suitable anode and a cathode of magnesium.

In testimony whereof I have signed my 55 name to this specification in the presence of two subscribing witnesses.

ANSON GARDNER BETTS.
